SASH MUNTIN CONSTRUCTION

Edmund Peremi, Bayside, N. Y., and Henry Weinmann, Brentwood, Mo., assignors, by mesne assignments, to General Bronze Corporation, Garden City, N. Y., a corporation of New York

Original application February 14, 1946, Serial No. 647,560. Divided and this application June 8, 1948, Serial No. 31,806

8 Claims. (CL 189—76)

1

The subject matter of this application is divided out of our copending application Serial No. 647,560, filed February 14, 1946, now Patent Number 2,473,298 issued June 14, 1949.

This invention relates to a metal window sash and frame construction.

An object of the invention resides in the provision of a window frame and sash construction that lends itself to standardization to such an extent that the frame may be used with various window opening constructions and so that the muntin patterns may be arranged or rearranged by the builder after the window frames and sashes have been delivered to the job.

With these and other objects in view, such as will appear as this description progresses, the invention resides in the combination and arrangement of parts illustrated in the drawings, described in the specification and recited in the claims.

In the drawings, wherein we have shown one form of the invention:

Figure 1 is a vertical elevation of the inside of a window frame and sashes constructed in accordance with our invention;

Figure 2 is a fragmentary perspective view of a typical muntin construction;

Figure 3 is an exploded view showing the manner in which the muntins are secured together at their intersection;

Figure 4 is a perspective view of the resilient clip used in combination with the muntins.

Referring to Figure 1, which shows a complete window including the frame and sash, the header of the frame is indicated by the reference numeral 10, the sill by the reference numeral 11 and the jambs by the reference numeral 12. The side rails of the upper sash are indicated by the reference numerals 13 and 14 and the horizontal upper and lower rails by the reference numerals 15 and 16, respectively. The side rails of the lower sash are indicated by the reference numerals 17 and 18 and the upper and lower rails of the lower sash by the reference numerals 19 and 20 respectively. These sash are of the double hung type and are slideable in the usual channels in the jambs.

We have shown the lower sash as being free of muntins and the upper sash as having cross muntins with three lights over three lights, but it is to be understood that the lower sash may have muntins and the number of lights may be varied.

In order that the muntins may be arranged in different designs by the builder on the job we

2

have provided for various arrangements of the muntins in the sash. For illustrative purposes we will describe the muntin arrangement in connection with the upper sash (see Figure 1). In this arrangement a horizontal muntin 21 and vertical muntins 22 and 23 are provided. At their points of intersection 24 these muntins are interlocked in the manner illustrated in Figures 2 and 3, as will later be described. Each of the muntins, where it contacts the rail of the sash, is provided with a lip 25 (see Figure 2) and at these points the rails have holes formed therein for the reception of self-threading screws 26. Thus the sash may be given the muntin design illustrated in Figure 1. However, so that this muntin design may be changed by the builder on the job, additional holes are formed in the rails of the sash. For instance, the sash may be provided with a hole at the points 26, which will permit the use of one horizontal and one vertical muntin. Of course additional holes in the rails of the sash may be provided vertically to make it possible to use other muntin patterns.

Where the muntins intersect, as for instance at 24, the muntins are secured together. This intersection and securing together of the muntins is accomplished by the following means. For illustrative purposes we will describe the muntin intersections shown in Figure 2, and in connection with this description will refer also to Figure 3. The flange 27 of the muntin 22 is recessed at 28 and the web 29 is recessed at 30, the recesses 28 and 30 communicating as illustrated in Figure 3. The web 31 of the muntin 21 is recessed at 32, which recess communicates with a recess 33 in the glazing bead 34. Thus when the two muntins are assembled the flange 35 of the muntin 21 will lie within the recess 28 of the muntin 22 and the webs 29 and 31 of the muntins 21 and 22 will interlock. Because of the presence of the recesses 30, 32 and 33, the glazing bead 36 of the muntin 22 will lie within the recess 33 of the muntin 21. Thus the muntins will be interlocked at their points of intersection with their faces flush.

To preclude separation of the muntins at their intersections each intersection is provided with a pair of spring clips (see Figure 2), which are designed to forcibly maintain the muntins in their assembled positions. The free ends 37 and 38 of each of these clips are engaged beneath the lip 39 of the adjacent glazing bead to maintain the clips in position. The free ends 37 and 38 of each of the clips resiliently force the intermediate portion of the clips against the flanges

27 and 35, bridging them at their intersection at the recess at 28. The clips exert sufficient force against the muntins to maintain the muntins in their assembled positions, but they may be removed to permit the disassembling and rearrangement of the muntins.

While we have illustrated and described the particular form of our invention it is to be understood that various changes may be made within the scope of the claims, and we, therefore, do not wish to be limited to the illustrated form except insofar as limitation is made necessary by the claims.

We claim:

1. In a sash construction, horizontal and vertical rails, crossed muntins secured to said rails, said muntins at their points of crossing being recessed and interlocked with their inner and outer faces substantially flush, and removable resilient clips engaging the crossed muntins at their points of crossing, and constructed and arranged to maintain said muntins in their interlocked condition, said muntins having glazing grooves therein, and said clips being entirely located within said grooves.

2. In a sash construction, horizontal and vertical rails, crossed muntins extending between and secured to said rails, said muntins at their points of crossing being recessed and interlocked with their inner and outer faces substantially flush, said muntins having glazing grooves and grooved glazing beads, and removable resilient clips engaging said muntins at their points of crossing and entirely located within said glazing grooves and having portions engaged within said glazing beads.

3. In a sash construction, horizontal and vertical rails, crossed muntins extending between and secured to said rails, said muntins at their points of crossing being recessed and interlocked with their inner and outer faces substantially flush, said muntins having glazing grooves and grooved glazing beads, and removable resilient clips engaging said muntins at their points of crossing and entirely located within said glazing grooves and having portions extending longitudinally within and resiliently held within the grooves of said glazing beads.

4. In a window construction, a pair of muntins comprising inner and outer flanges, webs joining said flanges together, said muntins at their points of crossing being recessed and interlocked with their adjacent flanges in substantial alignment with each other, clips securing said muntins together at their points of crossing and located entirely in the space between said flanges, said clips having free end portions in longitudinal engagement with certain of said flanges and an intermediate resilient portion in engagement with the other of said flanges.

5. In a window construction, a pair of muntins comprising inner and outer flanges, webs

joining said flanges together, said muntins at their points of crossing being recessed and interlocked with their adjacent flanges in substantial alignment with each other, clips securing said muntins together at their points of crossing and located entirely in the space between said flanges, said clips having free end portions in engagement with certain of said flanges and an intermediate resilient portion in engagement with the other of said flanges.

6. In a window construction, a pair of muntins comprising inner and outer flanges, webs joining said flanges together, said muntins at their points of crossing being recessed and interlocked with their adjacent flanges in substantial alignment with each other, clips securing said muntins together at their points of crossing and located entirely in the space between said flanges, said clips having free end portions in longitudinal engagement with certain of said flanges and an intermediate resilient portion in engagement with the other of said flanges, said flanges with said free end portions of said clips are engaged having longitudinal grooves in which said free end portions are located.

7. In a window construction, a pair of muntins comprising inner and outer flanges, webs joining said flanges together, said muntins at their points of crossing being recessed and interlocked with their adjacent flanges in substantial alignment with each other, resilient devices removably located entirely between said flanges and exerting resilient pressure thereon to maintain said muntins in interlocked relationship.

8. In a window construction, a pair of muntins comprising inner and outer flanges, webs joining said flanges together, said muntins at their points of crossing being recessed and interlocked with their adjacent flanges in substantial alignment with each other, resilient devices removably located entirely between said flanges and exerting resilient pressure thereon to maintain said muntins in interlocked relationship, and glazing beads having grooves therein in which said resilient devices are engaged and by which they are secured in operative position.
